UNITED STATES PATENT OFFICE.

ROBERT J. STUART, OF POUGHKEEPSIE, NEW YORK, ASSIGNOR TO THE SEDGWICK MANUFACTURING COMPANY, OF SAME PLACE.

PAPER-FEEDING MACHINE.

SPECIFICATION forming part of Letters Patent No. 319,431, dated June 2, 1885.

Application filed January 29, 1884. (No model.)

To all whom it may concern:

Be it known that I, ROBERT J. STUART, of the city of Poughkeepsie, in the county of Dutchess and State of New York, have invented new and useful Improvements in Paper-Feeding Machines, of which the following is a specification.

This invention relates to an improvement in that class of machines which are employed for feeding sheet-paper to ruling, folding, and calendering machines, printing-presses, and other kinds of machines in which sheet-paper is used.

The invention relates more particularly to a machine by which the top sheet is removed from the pile of paper by turning the top sheet so as to separate it from the pile and bring it within reach of the carrying rollers or tapes which move the sheets onward one after another.

20 A machine of this description is described, shown, and claimed in Letters Patent of the United States No. 282,014, granted to me July 24, 1883; and my present invention consists of improvements on this machine, and has the 25 object to render the machine more efficient and reliable in its operation.

My invention consists of the improvements which will be hereinafter fully set forth, and pointed out in the claims.

30 In the accompanying drawings, consisting of five sheets, Figure 1 is a side elevation of my improved machine; Fig. 2, an end elevation of my improved machine. Fig. 3 is a top plan view of the machine. Fig. 4 is a vertical sectional elevation of the pivot resting on the paper and the parts connected therewith. Fig. 5 is a horizontal section of the horizontal arm secured to the upper end of the pivot-spindle. Fig. 6 is a side elevation of the mechanism whereby the 40 upper carrying-rollers are raised and lowered. Fig. 7 is a cross-section of the side frames and feed-screws. Fig. 8 is a horizontal section in line xx , Fig. 7. Fig. 9 is a side elevation of the gear mechanism whereby the counter-shaft 45 is driven from the driving-shaft. Fig. 10 is a side elevation of the device whereby the rock-lever of the buckling mechanism is actuated. Fig. 11 is a side elevation of the mechanism whereby the pivot-lifting device is actuated.

50 Fig. 12 is a longitudinal sectional elevation

showing the holding fingers and buckling device resting on the pile of paper. Fig. 13 is a cross-section of the same devices. Fig. 14 is a top plan view of the adjustable foot resting on the paper. Fig. 15 is a horizontal section in line xx , Fig. 4. Fig. 16 is an elevation of the pivot. Fig. 17 is a vertical section of the gage or foot resting on the paper and the parts connected therewith. Fig. 18 is an elevation of the outer side of that portion of the side frame which is adjacent to the foot resting on the paper. Fig. 19 is a perspective view of one of the fingers whereby the top sheet is moved.

Like letters of reference refer to like parts in the several figures.

A A represent the side frames of the machine, connected by cross-stays $a a$.

A' represents the feed-table, upon which the pile of paper A² is placed. The feed-table A' is secured to supports a' , which are provided, 70 near their outer ends, with screw-nuts a^2 and upright extensions a^3 , having rollers a^4 , which run in vertical grooves a^5 , formed on the inner sides of the side frames, A, whereby the feed-table is guided in its vertical movements.

b represents vertical feed-screws, which work in the screw-nuts a^2 , secured to the feed-table, and which are held against lengthwise movement in bearings b' , secured to the side frames, A.

B represents a hand-wheel secured to the upper end of one of the feed-screws, and provided on its under side with an annular ratchet-rim, b^2 . The lower ends of the feed-screws are connected by a horizontal shaft, b^3 , and 85 bevel-wheels b^4 , so that both feed-screws are actuated simultaneously.

C represents the vertical pivot, which rests upon the pile of paper and forms a center on which the top sheet is turned. The upper 90 portion of the pivot C is provided with a tubular socket, c , in which is fitted the lower end of an upright spindle, c' .

c' is a tubular bearing or sleeve, in which the upper portion of the spindle c' turns, and 95 which passes through a screw-nut, c^2 . The latter is fitted in an elongated opening, d , formed diagonally in a transverse brace or bar, D, which connects the upper ends of the side frames, A. The screw-nut c^2 is secured in po- 100

sition in the elongated opening d by a hand-nut, c^4 , applied to the upper end of the externally-threaded sleeve c^2 and bearing against the upper side of the slotted brace D , and a 5 collar or flange, c^5 , formed at the lower end of the sleeve c^2 and bearing against the lower side of the slotted brace D , as represented in Fig. 4. Upon releasing the hand-nut c^4 the nut c^3 is loosened in the slot d and can be adjusted back and forth in the same, thereby 10 adjusting the pivot C toward or from the middle of the feed-table, as may be necessary with sheets of different sizes. The pivot C has a limited vertical movement on the spindle c' .

15 E represents a curved arm, which is rigidly secured with its upper end to the spindle c' , and which is provided at its lower end with a bifurcated bearing, e , in which turns a horizontal shaft, e' .

20 e^2 represents an arm, which is firmly secured to the horizontal shaft e' , between the jaws of the bearing e , and which straddles with its bifurcated end e^3 the upper portion of the pivot C . The latter is provided with recesses 25 or depressions e^4 in which the ends e^3 of the arm e^2 engage, so that the horizontal shaft e' receives a rocking motion when the pivot C is raised or lowered.

25 F represents the fingers, which are secured to the horizontal shaft e' and provided at their ends with bearing-pieces f , of rubber or other similar material, which rest upon the paper and turn and move the top sheet during the forward movement of the fingers.

30 g is a horizontal rock-shaft, which is supported in bracket-bearings $G G$, secured to the ends of the slotted central portion of the cross-piece D .

35 g' is an arm, which is secured to the rock-shaft g , and which straddles with its bifurcated end the upper portion of the pivot C . The latter is provided with an annular groove, g^2 , in which the bifurcated end of the arm g' engages, so that the pivot can be raised and lowered 40 on the spindle c' by the arm g' while the pivot is being turned.

40 H represents an arm secured to the upper end of the spindle c' for turning the same, and h is a connecting-rod, whereby the arm H is connected with the actuating rock-lever I . The arm H is provided with a slot, h' , in which is arranged an adjustable block, h^2 , which can be moved toward and from the spindle c' by an adjusting-screw, h^3 , and which is clamped 45 by a screw-nut, h^4 , in position in the slot h' after it has been adjusted. The block h^2 is provided on the outer side of the arm H with a vertical socket in which is pivoted a bifurcated carrier, h^5 , to which the inner end of the 50 connecting-rod h is attached by a horizontal bolt, h^6 . This bolt forms a universal joint with the vertical pivot h^7 , by which the carrier h^5 is attached to the block h^2 , thereby giving the connecting-rod h the requisite freedom 55 of movement.

60 j represents the horizontal driving-shaft, arranged transversely in the machine and sup-

ported in bearings in the side frames, A . j' represents a counter-shaft arranged below the driving-shaft j and parallel with the same. 70 Motion is transmitted from the driving-shaft j by a train of gear-wheels, $J J' J''$, in such manner that the speed of the counter-shaft j' can be increased or reduced by changing the size of the gear-wheel J'' and adjusting the 75 gear-wheel J' accordingly.

J^3 represents a clutch-coupling, whereby the driving-pulley J^4 can be connected or disconnected, as desired.

j^2 represents a rock-shaft arranged in rear of the driving shaft j and parallel therewith. The rock-arm I is secured to the rock-shaft j^2 , and the latter is set in motion by an eccentric, I' , secured to the counter-shaft j' and connected with a downward extension, i , of the rock-arm I . The upper end of the rock-arm I is connected with the connecting-rod h by a universal joint composed of a bearing, i' , secured to the upper end of the arm I by a horizontal bolt, i^2 , and a bearing, i^3 , in which the outer end of the connecting-rod is secured, and which is attached to the bearing i' by a vertical bolt, i^4 .

K represents an elbow-lever, which is mounted loosely upon the rock-shaft j^2 , and provided 95 at the end of its lower arm, k , with a roller, k' .

k^2 is a cam secured to the counter-shaft j' , opposite the roller k' , so as to actuate the elbow-lever K .

k^3 represents the upper arm of the elbow-lever, and k^4 a rod, whereby this arm is connected with an arm, k^5 , secured to the horizontal rock-shaft g . The cam k^2 moves the lower arm of the lever K forwardly, and thereby rocks the shaft g in its bearings in an 100 upward direction, which movement is transmitted by the arm g' to the tubular pivot C , and from the latter through the arm e^2 to the rock-shaft e' , whereby the fingers F are lifted from the paper. This movement occurs when 105 the fingers F have completed their forward movement, and the parts are held in this elevated position by the cam k^2 until the fingers have completed their backward movement, when the cam k^2 releases the lever K and thereby permits the parts to descend to their 110 former position, in which the pivot C and fingers F rest upon the top sheet.

The forward and backward movement of the fingers F is effected by the rock-arm I and the parts whereby the said rock-arm is connected with the spindle c' , and the tubular pivot C turns on the spindle c' with the fingers by reason of the arm e^2 engaging in the recesses e^4 of the pivot. 120

The arm g' is made adjustable on the shaft g , so that it can follow the adjustment of the pivot in the slot d of the bracket D .

l represents a finger, which is pivoted to a bracket, L , secured to a cross-piece, L' , connecting the side frames, A , and which rests with its free end upon the corner of the pile adjacent to the buckling device. The finger l is held down upon the paper by a spiral spring, 130

l', which is secured to a collar, *l*', on the rock-shaft *j*'.

5 *M* represents the buckling-finger, which is pivoted to the rock-arm *I* by a bolt, *m*, passing through a slot, *m'*, in the rock-arm, so that the finger can be adjusted backward or forward, as may be necessary. The free end of the finger *M* is provided with a bearing-piece, *m*', of rubber or other suitable material, resting upon the paper in front of the finger *l*.

10 *m*' is a roller or stud attached to the finger *M*, and adapted to ride upon the upper side of the finger *l* during the last portion of the backward movement of the finger *M*, whereby the finger is lifted from the paper and its pressure added to that of the finger *l*, whereby the pile is more securely held in place on the feed-table.

15 *n* represents a supplemental pressure-finger adapted to bear upon the further corner of the pile on the same side of the machine on which the finger *l* is arranged. The finger *n* is attached to an elbow-lever, *N*, which is pivoted to the bracket *L* at *n'*. The finger *n* is secured to the lever *N* by a bolt, *n*', passing through a longitudinal slot, *n*', in the upper arm of the lever *N*, so that the finger *n* can be adjusted toward or from the finger *l*, according to the size of the sheets operated upon. The elbow-lever *N* is actuated by a cam or crank, *n*'', secured to the counter-shaft *j*' in such manner that the finger *n* is lifted from the top sheet when the same is moved out from under the finger by the fingers *F*. 30 At all other times the finger *n* is held down upon the top sheet by a spring, *n*'''', connecting the upper arm of the lever *N* with the stationary frame of the machine.

35 *O* represents a gage or foot, which rests upon the top sheet between the fingers *l* and *n*, and which serves the double function of regulating the upward feed motion of the table *A'*, and of operating, in connection with the finger *M*, as a buckling device. During the forward movement of the finger *M* the foot *O* rests upon the top sheet in front of the bearing-piece *m*' of the finger *M*, whereby the top sheet is buckled and separated from the pile, as represented in Fig. 12.

40 The foot *O* is provided with an upwardly-projecting screw-stem, *o*', which works in a threaded opening in a horizontal arm, *o*'', and is secured in position on the same after being adjusted by a jam nut, *o*'''. The arm *o*'' is attached to an inwardly-projecting arm, *o*''', formed on an upright rod, *o*'''. The arm *o*'' is attached to the arm *o*'' by a vertical bolt, *o*''', passing through a longitudinal slot, *o*''', in the arm *o*''', whereby the position of the foot *O* can be adjusted with reference to the buckling-finger *M* as may be necessary in order to properly buckle the top sheet. The upper end of the rod *o*''' is guided on the adjacent side frame, *A*, by a horizontal bolt, *p*, which passes through a vertical slot, *p*', in the side frame. The lower end of the rod *o*''' is attached to an elbow-lever, *P*, which is pivoted to the side

frame, *A*, at *p*''', and which has its short arm *p*'' provided with a roller, *p*'''. The latter is operated upon by a cam, *p*''', secured to the counter-shaft *j*', and formed in such manner that it will cause the foot *O* to be lifted from the top sheet when the latter is ready to be withdrawn from under the foot *O* by the fingers *F*. The foot *O* is held down on the top sheet by a spring, *p*''', connecting the arm *o*''' with the stationary frame of the machine.

45 *q* represents a pawl, which engages with the ratchet-rim *b*' on the hand-wheel *B*. The pawl *q* is pivoted to the upper end of an elbow-lever, *Q*, which is pivoted to the outer side of the adjacent side frame, *A* at *q*'. The lower arm of the lever *Q* is provided with a roller, *q*'', which is operated upon by a cam, *q*''', secured to the counter-shaft *j*'. The cam *q*''' is so formed that it will produce a rocking motion in the lever *Q*, thereby moving the pawl *q* back and forth over the ratchet-rim *b*'.

50 *q* is a projection or nose formed on the lower arm of the lever *Q* and engaging against a shoulder, *q*'''', on the outer side of the lever *P*, whereby the stroke of the lever *Q* and the motion which the pawl *q* produces in the ratchet-wheel *b*' are regulated. In the same measure as the foot *O* descends by the removal of the sheets from the top of the pile the lever *P* and the stop *q*''' descend also, whereby the oscillation of the lever *Q* and the stroke of the pawl *q* are increased, so that the rotation of the wheel *B* and the feed-screws is proportionate to and controlled by the amount of paper which is removed from the top of the pile. The pawl *q* is held in engagement with the ratchet-rim *b*' by a spring, *r*, which connects the heel of the pawl with a lever, *R*, pivoted to the outer side of the adjacent side frame, *A* at *r*'. The end of the lever *R* adjacent to the upright rod *k*' is bent at right angles to the main portion of the lever *R*, which extends along the outer side of the side frame, *A*. 55 This bent portion of the lever *R* engages under a stop, *o*'''', on the rod *o*'''', and a stop, *r*''', on the rod *k*'.

60 Upon depressing the handle *r*'' of the lever *R*, the bent portion of the lever *R* is raised, thereby raising the rods *o*''' and *k*' and lifting the foot *O*, the pivot *C*, and the fingers *F* from the pile. The spring *r* is released at the same time, thereby disengaging the pawl *q* from the ratchet-rim *b*'. The feed-table can now be lowered for supplying a fresh charge of paper to the machine by turning the hand-wheel *B*. The lever *R* can be locked in this position during this operation by a turn-button, *r*''', pivoted to the side frame.

65 *S* represents the grooved tape-roller, arranged in front of the feed-table *A'*, with its upper side in line with the top sheet, so as to receive on its upper surface the top sheet as the latter is removed from the pile by the fingers *F*. The roller *S* is provided with carrying-tapes in any usual and well-known manner.

70 *S'* are rollers mounted upon a horizontal

shaft, s , and faced with india-rubber or other suitable material, so as to bite against the paper when brought in contact therewith. The shaft s is journaled in arms s' , which are secured to a transverse rock-shaft, s^2 , which is journaled in the side frames, A. The rollers S' are raised and lowered by an eccentric or cam, s^3 , mounted on the counter-shaft j' and engaging with a bell-crank lever, s^4 , which is pivoted to the inner side of the adjacent side frame, and provided at the end of its lower arm with a roller, s^5 , which bears against the eccentric s^3 . The upper arm of the lever s^4 is connected with one of the arms s' by a connecting-rod, s^6 . The eccentric s^3 is so formed and arranged upon the shaft j' that the rollers S' are held in an elevated position, as represented in Fig. 6, while the top sheet is being fed on the roller S, and so that the rollers S' are lowered and caused to press upon the top sheet when the front portion thereof has been properly placed on the roller S. In this position of the rollers S' the top sheet is clamped between the rollers S S', and thereby moved forwardly on the tapes which pass around the lower roller, S. When the sheet has cleared the rollers S S', the rollers S' are again elevated by the above-described mechanism.

The operation of the machine is as follows: The pile of paper being placed upon the feed-table A', the fingers l and n , the foot O, the pivot C, and the fingers F all rest upon the top sheet. The forward movement of the finger M draws the corner of the top sheet from under the finger l , and buckles the corner of this sheet against the foot O, thereby separating the top sheet from the pile. The return movement of the finger M carries the corner of the top sheet back upon the finger l , the end of the latter being sharpened to allow the sheet to slide upon the top of the finger. The finger M, resting on the finger l , holds the latter more tightly upon the feed-table. The curvilinear movement of the fingers F now causes the top sheet to be turned on the pile toward the rollers S S', and the foot O and finger n are lifted by their actuating mechanism in order to permit the fingers F to move the top sheet away from under the finger n and the foot O. In turning the top sheet on the pile toward the rollers S S', the pivot C acts as a center or fulcrum on which the top sheet turns. The forward movement of the fingers F continues until the front edge of the top sheet has been squarely placed upon the roller S. When this has been accomplished, the rollers S' descend and grip the front edge of the top sheet, and the latter is now fed forward, by the rollers S S', upon the carrying-tapes. Before the top sheet has been gripped by the rollers S S' the fingers F and the pivot C are lifted from the pile by the action of the cam k^2 and connecting parts, to allow the turned top sheet to be carried off by the rollers, and are held in an elevated position during the return movement of the fingers. When

the fingers F have completed their return-stroke, they are again dropped, together with the pivot C, upon the paper, and the next forward movement of the fingers begins, whereby the sheet which is now on the top of the pile is turned and moved forward between the rollers S S'.

By changing the position of the pivot C in the elongated opening d and properly adjusting the parts connected therewith, the mechanism whereby the top sheet is turned and moved forward is adjusted to the size of the sheet operated upon.

In Fig. 3 the position of the pile of paper on the table is indicated in full lines, and the top sheet is represented in dotted lines in one of the positions which it assumes while it is being turned on the pile.

I claim as my invention—

1. In a machine for feeding sheets of paper from a pile, the combination, with a vertically-movable bed supporting the pile, of a gage resting on the pile, mechanism, substantially as described, whereby the gage controls automatically the movement of the pile-supporting bed, a buckling-finger operating, in connection with said gage, to buckle the top sheet, and a rubbing-finger having a curvilinear motion in a plane parallel with the pile-supporting bed, whereby the top sheet is turned on the pile and moved forward, substantially as set forth.

2. In a machine for feeding sheets of paper from a pile, the combination, with a vertically-movable bed supporting the pile, of a gage resting on the pile, mechanism, substantially as described, whereby the gage controls automatically the movement of the pile-supporting bed, a buckling-finger operating, in connection with said gage, to buckle the top sheet, a pivot resting on the pile, and a rubbing-finger having a curvilinear motion, whereby the top sheet is turned and removed, substantially as set forth.

3. In a machine for feeding sheets of paper from a pile, the combination, with the stationary frame, pile-supporting bed, and feeding-fingers, of a vertical spindle, a pivot fitted loosely on the lower end of the spindle, and mechanism, substantially as described, whereby the pivot can be raised and lowered on the spindle to bear upon the pile or clear the same, substantially as set forth.

4. In a machine for feeding sheets of paper from a pile, the combination, with the stationary frame, pile-supporting bed, and feeding-fingers, of a vertical spindle, mechanism, substantially as described, whereby a rocking motion is imparted to the spindle, a pivot fitted loosely on the spindle, and mechanism, substantially as described, whereby the pivot is raised and lowered on the spindle to bear upon the pile or clear the same, substantially as set forth.

5. In a machine for feeding sheets of paper from a pile, the combination, with the side frames, pile-supporting bed, cross-piece D,

and vertical spindle c' , of the pivot C, rock-shaft g , and arm g' , substantially as set forth.

6. The combination, with the cross-piece D, vertical spindle c' , and pivot C, of the rock-shaft e' , fingers F, attached thereto, arm e^2 , connecting the rock-shaft e' with the pivot C, rock-shaft g , and arm g' , connecting said rock-shaft g with the pivot, substantially as set forth.

10 7. In a machine for feeding sheets of paper from a pile, the combination, with the side frames, pile-supporting bed, and cross-piece D, provided with elongated opening d , of the spindle c' , screw-sleeve c^2 , screw-nut c^3 , and clamp-nut c^4 , pivot C, and feeding-fingers F, substantially as set forth.

8. In a machine for feeding sheets of paper from a pile, the combination, with the stationary frame, pile-supporting bed, and feeding-fingers F, of the spindle c' , provided with arm H, connecting-rod h , and rock-arm I, a pivot, C, fitted loosely on the spindle, and a rock-shaft, g , and arm g' , whereby the pivot is raised and lowered, substantially as set forth.

25 9. In a machine for feeding sheets of paper from a pile, the combination, with the stationary frame, pile-supporting bed, and feeding-fingers F, the spindle c' and pivot C, and the cross-piece D, having an elongated opening, d , of bearings G, secured to said cross-piece, a rock-shaft, g , supported in said bearings, and an arm, g' , connecting said rock-shaft with the pivot, and made lengthwise adjustable on said rock-shaft, substantially as set forth.

35 10. The combination, with the spindle c' and pivot C, of a bearing, E, secured to said spindle, a rock-shaft, e' , supported in said bearing, a finger, F, secured to said rock-shaft, and mechanism, substantially as described, whereby said rock-shaft is turned for raising and lowering the finger, substantially as set forth.

45 11. The combination, with the stationary frame, of a spindle, a pivot fitted loosely on the spindle, a rubbing-finger adapted to turn the top sheet, and mechanism, substantially as described, whereby the pivot and rubbing-finger are raised and lowered simultaneously, substantially as set forth.

50 12. The combination, with the gage resting on the pile, of holding-down fingers resting on the corners of the pile in front and in rear of the gage, and a rubbing-finger operating to buckle the top sheet against the gage, substantially as set forth.

55 13. The combination, with the adjustable feed-table, of a gage resting on the pile and made vertically adjustable in its support, and mechanism, substantially as described, whereby the gage controls the feed motion of the table, substantially as set forth.

14. The combination, with the feed-table, of the gage O, provided with a screw-stem, o' , slotted arm, o^2 , and rod, o^3 , connecting the gage with the mechanism, whereby the feed- 65 motion of the table is controlled, substantially as set forth.

15. The combination, with the feed-table, of the gage O, arm o^2 , rod o^3 , bolt p , and side frame, A, provided with vertical slot p' , substantially as set forth.

16. The combination, with the feed-table, gage O, hold-down finger l, and buckling-finger M, of the finger n, secured to the elbow-lever N, and adapted to rest upon the corner 75 or edge of the pile, and to be lifted when the top sheet is being drawn from under said finger, substantially as set forth.

17. The combination, with the feed-table, gage O, hold-down finger l, and buckling-finger M, of the finger n, secured to the elbow-lever N in the slot n^3 of the same, substantially as set forth.

18. The combination, with the lever R, of the gage O and rod o^3 provided with a stop 85 or shoulder, o^9 , adapted to be raised by the lever R, substantially as set forth.

19. The combination, with the lever R, of the pawl q, pivoted to the lever Q, and the spring r, connecting the pawl with the lever 90 R, substantially as set forth.

20. The combination, with the pivot C, rubbing-finger F, lever R, rod k^4 , and mechanism, substantially as described, whereby said rod is connected with the pivot and rubbing-finger, of a stop, r^2 , formed on said rod and adapted to be lifted by the lever R, whereby the pivot and rubbing-finger can be lifted from the pile, substantially as set forth.

21. The combination, with the gage O, pivot 100 C, and rubbing-fingers F, of the lever R, whereby all of said parts are lifted from the pile simultaneously, and mechanism, substantially as described, whereby the lever R is connected with said parts, substantially as set 105 forth.

22. The combination, with the feed-table and the vertically-movable gage-rod, of a horizontally-adjustable extension and a vertically-adjustable gage secured thereto, and adapted to be placed at varying distances from the buckling-finger, substantially as set forth.

Witness my hand this 18th day of January, 1884.

ROBERT J. STUART.
